UNITED STATES PATENT OFFICE.

EMILE JAECK, OF BROOKLYN, NEW YORK.

BED FOR ZINC PRINTING-PLATES.

SPECIFICATION forming part of Letters Patent No. 423,691, dated March 18, 1890.

Application filed November 15, 1889. Serial No. 330,400. (No model.)

To all whom it may concern:

Be it known that I, EMILE JAECK, of Brooklyn, in the county of Kings and State of New York, a citizen of the United States, have invented certain new and useful Improvements in Beds for Zinc Printing-Plates, of which the following is a specification.

This invention relates to improvements in beds for holding and supporting zinc plates used in the art of lithography.

The object of my invention is to provide a new and improved bed on which the zinc plate can be held securely and stretched so as to fit snugly on the top of the bed.

The invention consists in the construction and combination of parts and details, as will be fully described and set forth hereinafter, and pointed out in the claims.

In the accompanying drawings, Figure 1 is a vertical longitudinal sectional elevation of my improved zinc bed. Fig. 2 is a plan view of the same, parts being broken out and others in section on line 2 2, Fig. 1. Fig. 3 is a detail view of one end part of the bed.

Similar letters of reference indicate corresponding parts.

The plate A is provided with four side walls in the usual manner. One edge of the zinc sheet B is clamped between one side of the bed A and the bar C, which is drawn up closely against the side of the bed by bolts D. The other end of the zinc plate is passed over a roller E, mounted to turn in a groove in the front edge of the bed, and is clamped between two plates G and H by means of screws J; which plates are arranged at the front of the bed and are provided with guide-pins K, passing through vertical slots L in the front of the bed and provided at their inner ends with heads L', which heads prevent the plates from being moved from the

front of the bed, or tilting. The plate H is provided at each end with a lateral projection or wing M, and above the same the bed A is provided with an upright cylindrical bracket N, in which a screw O is mounted to turn, said screw having a square or other suitable upper end. After the zinc sheet B has been securely clamped between the plates G and H the screws O are turned so as to exert downward pressure on the wings M, thereby drawing the plates G and H downward, whereby the zinc sheet is stretched snugly over the top of the base A. The sheets can be applied easily and rapidly, and when they are to be detached can easily be released and removed.

Having thus described my invention, I claim as new and desire to secure by Letters Patent—

1. In a bed for zinc plates, the combination, with a base-plate or bed, of clamping-plates guided on one of the sides of the base to move vertically, one of said clamping-plates being provided with end wings, brackets on the base-plate above said wings, and screws in said brackets, substantially as set forth.

2. The combination, with a base-plate having vertical slots in its sides, of clamping-plates arranged adjacent to said vertically-slotted side, headed guide-pins projecting from one of the clamping-plates through the slots, wings on the ends of one of the clamping-plates, brackets on the base above said wings, and screws in said brackets, substantially as set forth.

In testimony that I claim the foregoing as my invention I have signed my name in presence of two subscribing witnesses.

EMILE JAECK.
